UNITED STATES PATENT OFFICE

ALFRED J. HEINKE, OF TOWACO, NEW JERSEY, ASSIGNOR TO H. R. MALLINSON & CO., OF NEW YORK, N. Y., A CORPORATION OF DELAWARE

DESIGN FOR A TEXTILE FABRIC OR THE LIKE

Application filed November 10, 1932. Serial No. 45,858. Term of patent 3½ years.

To all whom it may concern:

Be it known that I, ALFRED J. HEINKE, a citizen of the United States, residing at Towaco, Morris County, State of New Jersey, have invented a new, original, and ornamental Design for a Textile Fabric or the like, of which the following is a specification, reference being had to the accompanying drawing, forming, forming part thereof.

The figure is a surface view of a piece of textile fabric or the like, showing the design. The area within the dot and dash lines shows one complete unit of the design. The repeats are arranged in vertical rows and adjacent vertical rows are one half a complete unit offset so that the angle of the

complete unit indicated by letter A corresponds with angle B of one of the repeats in an adjacent vertical row. The leading features in my design consist of an artistic arrangement of a solid flower resembling blue anemones on a lined background outlining other flowers resembling white anemones. The vertical lines appearing in the drawing denote solid color which serves to accentuate the configuration of the individual flowers and give the background a spreckly effect.

I claim:

The ornamental design for a textile fabric or the like, as shown and described.

ALFRED J. HEINKE.
